CLAIM

We claim the ornamental design for an infrared portable broiler, as shown and described.

DESCRIPTION

FIG. 1 illustrates a perspective view of an infrared portable broiler of the present invention;

FIG. 2 illustrates a front elevational view thereof;

FIG. 3 illustrates a rear elevational view thereof;

FIG. 4 illustrates a top view thereof;

FIG. 5 illustrates a left side elevational view thereof; and,

FIG. 6 illustrates a right side elevational view thereof.

The broken lines illustrate portions of the infrared portable broiler which form no part of the claimed design.
